by Ernest D. Janan
Atty.

UNITED STATES PATENT OFFICE.

ALFRED WOELM, OF BERLIN, GERMANY, ASSIGNOR, BY MESNE ASSIGNMENTS, TO
PENCIL MECHANISM CORPORATION, A CORPORATION OF NEW YORK.

STEP-BY-STEP LEAD PENCIL.

Application filed June 1, 1923, Serial No. 642,858, and in Germany March 14, 1923.

This invention relates to mechanical pencils of the type wherein the lead is advanced by a step-by-step movement, and in certain of its more specific aspects relates to magazine lead pencils.

An object of the invention is to provide an improved mechanism for step-by-step pencils whereby a lead may be advanced with ease and certainty.

Another object is to provide a step-by-step pencil which may be operated and used with relatively small danger of breaking a lead therein.

Another object is to provide a pencil which is simple and sturdy of construction and which may be readily and economically manufactured and assembled.

Another object is to provide improved mechanism for step-by-step pencils which is adapted to be operated in response to the movement of one casing member toward another casing member.

Other objects of the invention will in part be obvious and will in part appear herein-after.

The present application is directed to certain improvements over the inventions described and claimed in the copending application of Alfred Woelm, Ser. No. 588,688, filed September 16, 1922, the copending application of Alfred Woelm, Ser. No. 180,000, filed March 31, 1927, constituting a division of said Woelm application, Ser. No. 588,688, and the copending application of Edward D. Feldman, Ser. No. 596,309, filed October 23, 1922.

The invention accordingly comprises an article of manufacture possessing the features, properties, and the relation of elements which will be exemplified in the article herein described and the scope of the application of which will be indicated in the claims.

For a fuller understanding of the nature and objects of the invention reference should be had to the following detailed description taken in connection with the accompanying drawing, in which:—

Fig. 1 is a longitudinal section through a magazine pencil constructed in accordance with my invention,

Fig. 2 a sectional elevation of the upper or inner tube with the lead propelling device in advanced position,

Fig. 3 a sectional elevation of the lower part of the pencil with the working parts in a different position,

Figs. 4-6 show details of the construction,

Fig. 7 is a detail of a modified form of double arm gripper lever, and

Fig. 8 is an enlarged view of the lower portion of Fig. 1.

In the exemplified embodiment of the invention, there is provided a casing comprising a lower section 2 and a longitudinally movable upper section 3. In order to provide a tip for the pencil the section 2 is formed, in the present instance, with a tapered lower end, and, in order to permit leads to be retained in and fed from the upper end of the pencil, the upper section 3 is formed to provide the side walls of a lead magazine. The lower end of the latter section is slightly reduced in diameter so as to fit closely, but slidably, within the section 2. A cap 4 covers the upper end of the section 3 and extends downwards and over the upper end of the section 2. An eraser 6 in an eraser socket 7 may be inserted into the upper end of the magazine section 3. This socket is provided with a projection 40 engaging a T-shaped slot 41 in the section 3 forming a bayonet joint. At its upper end the socket 7 is furnished with screw thread 42 over which the female screw thread of the cap 4 fits.

In the present exemplification there is provided a central lead guide tube 10 which serves to guide leads from the magazine to a point adjacent the tip of the pencil. The tube 10 is formed with an enlarged bore at its upper end to facilitate the entrance of the leads and a restricted bore at the lower end to centralize the leads as they pass through. The mouth is preferably further restricted and slotted so as to form fingers which will be forced outward when the lead is propelled through the mouth. A pair of diametrically opposed longitudinal slots are formed through the wall of the tube 10 through which the gripping jaws 24 pass and grip and feed the leads.

The tube 10 has fastened to its top a disk 17 against the under side of which abuts the upper end of the spiral spring 50. This disk forms the bottom of the lead magazine, the side walls of which are provided by the upper casing section 3.

The lower end of the tube 10 screws into an anchor member 14 fixed in the tapering end of the section 2.

Mounted upon the central tube 10 and capable of a limited longitudinal motion thereon is a sleeve 20 provided with diametrically opposed longitudinal slots flanked by projecting ears 22, 22 and between these are pivoted at 23, the double armed levers 24, the lower arms of which are the jaws which engage, grip and propel the leads.

Mounted upon the tube 10 and capable of a limited longitudinal motion thereon is a collar 26 against the upper side of which the lower end of the spring 50 abuts and tends to force the collar downward. The downward motion of the collar 26 is limited by tongues 46 cut out of the casing section 3 and bent inwards. The collar 26 is formed or provided with a cone 27, which will at times be forced between the upper arms of the double armed levers 24 and tend to separate them, while the lower ends of said levers will be made to approach until they grip the lead between them. The portions of the jaws which grip the lead are preferably provided with longitudinal notches 51, substantially as illustrated in Fig. 6.

The sleeve 20 carries near its lower end a loose disk 44 against the underside of which abuts the upper end of a helical spring 45 the lower end of which rests upon the stationary cone 14. The upper surface of the disk 44 is preferably recessed. By the action of the spring 45 the sleeve 20 through the agency of the disk 44 and the grippers 24 is forced upward upon the central tube 10 so that the ears 22 of the sleeve 20 are forced against the lower end of the inner section 3 of the casing. In the position shown in Fig. 1 the upper arms of the grippers 24 are in engagement with the cone 27 of the slideable collar 26 controlled by the spring 50, so that in this position the lower arms 24 are forced into engagement with the lead by the cone 27 through the agency of the upper arms of the grippers and hold the lead in the writing position.

The manner in which the exemplified pencil operates is as follows:—The portion 2 is firmly held, and by means of the cap 4 the upper section 3 of the holder is pressed downward from the position shown in Fig. 1. Thereby the sleeve 20 with the grippers 24 and the disk 44 are also forced downward, against the resistance of the spring 45, through the agency of the ears 22 which are in contact, with the lower end of the section 3. The lead is thus propelled by the grippers. The cone 27 at first takes part in this motion, until it strikes the shoulder 48 of the central tube 10, which takes place just before the grippers reach their lower position. In the lower position the bevelled inner surfaces 24' of the claws come in contact with the

lower edge of the slots of the central tube 10 and are thereby swung outward, so that they release the lead. If then the section 3 or cap 4 is released, the sleeve 20 is returned into the position shown in Fig. 1 by the compressed spring 45 through the agency of the open grippers 24 and the cone 27, in which position the upper arms of the grippers 24 are again forced outward by the cone 27 and the lower arms with the gripper jaws inward and into engagement with the lead which they secure in the writing position.

In order to facilitate the forcing apart of the upper gripper arms on the return to the upper position, these arms may at the inside be provided with cams 47, which strike against the upper edge of the slot in the central tube 10 and thereby separate the upper arms.

This construction has the advantage that owing to the spring 50 the holding device of the lead is as a unit resiliently secured within the pencil, so that this device as a whole can be forced inwards against the pressure of the spring 50, as shown in Fig. 3, without the lead being released by the grippers 24. In this manner a resilient arrangement of the lead is obtained which prevents breakage of the lead to the greatest possible extent.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

What I claim is:—

1. In a magazine lead pencil; an outer casing; an inner casing slideable within and projecting somewhat above the outer casing, and having lead feeding means associated with its lower end; the lower part of the outer casing having a slotted guide tube mounted therein the upper end of which extends into the inner casing and is there expanded to form the bottom of a lead magazine; a sleeve with double armed levers pivoted therein slideable on said guide tube; a disc slideable upon said sleeve below said levers; a spring forcing said disc against the lower end of said levers; a cone shaped collar slideably mounted on said guide tube within said inner casing and adapted at times to separate the upper arms of said levers; and a spring compressed between said collar and the enlarged end of said guide tube.

2. In a magazine lead pencil; an outer casing; an inner casing movable longitudinally of the outer casing; the lower part of the

- outer casing having a slotted lead guide tube mounted therein; feeding mechanism comprising gripper levers pivoted in a sleeve slidable on said guide tube and adapted to grip a lead strip therein; said mechanism adapted to be forced downward by a downward movement of said inner casing; gripper actuating means mounted resiliently in said inner casing; and a spring applying pressure against the lower end of said gripper levers to force said mechanism upwards and braking force to retard swinging movement of said gripper levers.
3. In a magazine lead pencil; an outer casing; an inner casing movable longitudinally of the outer casing; the lower part of the outer casing having a slotted lead guide tube mounted therein; feeding mechanism comprising gripper levers pivoted in a sleeve 20 slidable on said guide tube and adapted to grip a lead strip therein, said mechanism adapted to be forced downward by a downward movement of said inner casing; a cone shaped collar mounted on said guide tube and 25 adapted to close said grippers; means for forcing said grippers open prior to their reaching their limit of downward travel, and closed prior to reaching the limit of their upward travel; and a spring applying force 30 against the lower end of said gripper levers.
4. In a magazine lead pencil; an outer casing; an inner casing movable longitudinally of the outer casing; the lower part of the outer casing having a slotted lead guide tube mounted therein; feeding mechanism comprising gripper levers pivoted in a sleeve 35 slidable on said guide tube and adapted to grip a lead therein, said mechanism adapted to be forced downward by like movement of said inner casing; gripper actuating means mounted in said inner casing; a spring applying pressure against the lower end of said gripper levers to force said mechanism upwards and braking force to retard swinging 40 movement of said gripper levers; and abutments in the path of said gripper levers adapted to force them open prior to their reaching the limit of their downward travel.
5. In a magazine lead pencil; an outer casing; an inner casing movable longitudinally of the outer casing; a slotted guide tube with an enlarged upper end mounted in the lower part of said outer casing; double armed gripper levers pivoted in a sleeve slidable 55 on said guide tube and adapted to contact with the lower end of said inner casing; means for applying resilient pressure against the lower ends of said levers; and means mounted in said inner casing for normally maintaining said grippers in closed position.
6. In a feeding mechanism for a magazine lead pencil; a guide tube with a longitudinal slot therein; a double armed lever pivoted in a sleeve slidable on said guide tube; a cam 60 face on the lower arm of said lever adapted to contact with the lower edge of said slot and force said arm outward and release the grip.
7. In a feeding mechanism for a magazine lead pencil; a guide tube with a longitudinal slot therein; a double armed lever pivoted in a sleeve slidable on said guide tube; a cam face formed on each arm of said lever and adapted to contact with the end of said slot and force the arm outward and away 75 from the tube.
8. A feeding mechanism for a magazine lead pencil, comprising a slotted guide tube stationary in the lower part of the pencil casing; gripping and feeding mechanism reciprocal on said guide tube the gripping parts thereof adapted to work through the slots in said guide tube; a spring supporting said gripping and feeding mechanism; and a second spring adapted to resist upward 80 movement of said mechanism.
9. In a magazine lead pencil having a two part casing one telescoping within the other: a reciprocal spring controlled gripping and feeding device normally gripping a lead and adapted to be actuated so as to force the lead downward by the displacement of a part of said casing in opposition to the controlling spring; and means whereby excess pressure applied against the lower end of the lead will cause said lead, and said gripping and feeding device, to move upward within said casing to a point where no further pressure can normally be applied thereto and to be returned to normal position when said excess 90 pressure is removed.
10. In a magazine lead pencil, the combination of: a two part tubular casing one telescoping in the other; a reciprocal spring controlled gripping device normally gripping a lead in transit from the magazine to the discharge opening of the pencil and adapted to be moved downward in opposition to its controlling spring by the longitudinal displacement of a part of said casing 100 and to be returned to normal under the urge of said spring, the cycle of movement of said device first feeding the lead downward, then releasing its grip thereon and re-gripping same at a higher point; and means whereby the lead is permitted to retreat within the casing, without being released by the gripping device, when excess pressure is applied against the point thereof, and is returned to normal when such excess pressure is removed.
11. In a magazine lead pencil, an outer casing, an inner casing slidable within and projecting somewhat above the outer casing, a pair of pivoted jaws adapted to be reciprocated longitudinally in response to longitudinal movement of said inner casing, spring actuated means normally holding said jaws in engagement with a lead in the pencil, and means to move said jaws out of gripping 110 position when said inner casing and said jaws 115
12. In a magazine lead pencil; an outer casing, an inner casing slidable within and projecting somewhat above the outer casing, a pair of pivoted jaws adapted to be reciprocated longitudinally in response to longitudinal movement of said inner casing, spring actuated means normally holding said jaws in engagement with a lead in the pencil, and means to move said jaws out of gripping 120 position when said inner casing and said jaws 125
13. In a magazine lead pencil; an outer casing, an inner casing slidable within and projecting somewhat above the outer casing, a pair of pivoted jaws adapted to be reciprocated longitudinally in response to longitudinal movement of said inner casing, spring actuated means normally holding said jaws in engagement with a lead in the pencil, and means to move said jaws out of gripping 130 position when said inner casing and said jaws

- are in an advanced position, the aforesaid elements being so associated as to maintain said jaws out of gripping position during at least a portion of the retractive movement of said jaws.
12. In a step by step pencil, the combination of a longitudinally movable member, a lead guiding tube formed with a plurality of longitudinal slots therein, a plurality of jaws normally extending into said slots to grip a lead in said tube, said jaws being longitudinally reciprocable in response to the operation of said longitudinally movable member, the outer surfaces of said jaws being formed with cam portions cooperating with the lower and upper ends of said slots respectively to move said jaws out of engagement with the lead toward the end of their downward movement and to move said jaws into engagement with the lead toward the end of their upward movement.
13. In a step by step pencil, the combination of a longitudinally movable member, a plurality of jaws adapted normally to grip a lead therebetween and to hold the same in writing position, said jaws being movable downwardly in response to downward movement of the longitudinally movable member and movable upwardly in response to upward movement of the longitudinally movable member, cam means to spread said jaws towards the end of their downward movement and means to return said jaws to gripping position toward the end of their upward movement.
14. In a step by step pencil, the combination of a longitudinally movable member, a plurality of jaws adapted normally to grip a lead therebetween and to hold the same in writing position, said jaws being reciprocable longitudinally in response to longitudinal movement of said longitudinally movable member, cam means to spread said jaws toward the end of their downward movement, and means to return said jaws to gripping position toward the end of their upward movement.
15. In a step-by-step pencil, the combination of a plurality of longitudinally movable lead gripping jaws arranged to normally hold a lead in writing position therebetween and to permit an upward movement of the lead in response to excess pressure applied to the lower end thereof, means for moving said jaws downwardly from their normal lead holding position to advance the lead, means to retract said jaws to normal position, and jaw spreading means operative to prevent the retraction of the lead by said jaws during at least a part of the jaw retracting operation of the last mentioned means.
16. In a magazine lead pencil, the combination of a plurality of longitudinally movable lead gripping jaws arranged normally to hold a lead in writing position, spring actuated means tending to maintain said jaws in lead gripping position, said means being arranged to permit upward movement of said jaws in response to pressure on the lower end of a lead gripped thereby and to lower said jaws to normal position when said pressure is removed, jaw advancing and jaw retracting means to move said jaws downwardly from their normal position to advance the lead and to return said jaws to normal position, and means to render said spring actuated means inoperative during at least a portion of the upward movement of the jaws to normal position.
17. In a pencil mechanism, the combination of a plurality of longitudinally-movable lead-gripping jaws, and means including a longitudinally-movable member to move the jaws and the lead downwardly as a unit during the major part of the downward movement of the longitudinally-movable member, to cause the jaws to release the lead during the latter part of the downward movement of said longitudinally-movable member, to move the jaws upwardly while out of gripping engagement with the lead during the major portion of the upward movement of said longitudinally-movable member, and to move said jaws into engagement with the lead at a higher point thereon during the latter part of the upward movement of said longitudinally-movable member.
18. In a step-by-step pencil, the combination of a plurality of longitudinally-movable lead gripping jaws, means normally to hold said jaws in an upward position and in firm gripping engagement with a lead in the pencil, means to move said jaws downwardly, means to thrust said jaws out of gripping engagement with the lead toward the end of their downward movement, and means to move said jaws upwardly while out of gripping engagement with the lead and to cause said jaws to re-engage the lead at a higher point.
19. In a pencil mechanism, the combination of a plurality of longitudinally-movable rockingly-mounted lead-gripping jaws, and operating mechanism comprising means normally to hold said jaws in an upward position and in firm gripping engagement with a lead in the pencil, means to move the jaws and the lead downwardly as a unit, means operative towards the end of the downward movement of the jaws to move the same out of gripping engagement with the lead, means to return the jaws to their normal upward position, and means to cause the jaws to re-engage the lead toward the end of their upward movement.
20. In a step-by-step pencil, the combination of a plurality of longitudinally-movable grippers provided with longitudinally extended lead-gripping surfaces, and operating mechanism comprising means normally to

hold said grippers in gripping engagement with a lead in the pencil, to move the grippers and the lead downwardly together, to cause the lead to be released by the grippers, to move the grippers upwardly while out of engagement with the lead, and to cause the grippers to re-engage the lead at a higher point.

21. In a step-by-step pencil, the combination of a plurality of jaws each provided with a longitudinally extended lead-gripping surface, means normally to hold said jaws in an upward position and in firm gripping engagement with a lead in the pencil, means to move the jaws and the lead downwardly as a unit, means thereafter to move the jaws out of gripping engagement with the lead, and means to return the jaws to their upward normal position and to cause the jaws to re-engage the lead at a higher point.

22. In a step-by-step pencil, the combination of a longitudinally-movable lead-gripping unit, and operating mechanism comprising means normally to hold said gripping unit in firm gripping engagement with a lead in the pencil, means to move the gripping unit and the lead downwardly together, positive means to move the gripping unit out of engagement with the lead, and means to move the gripping unit upwardly while out of engagement with the lead and to cause the gripping unit to re-engage the lead at a higher point.

23. In a step-by-step pencil, the combination of a plurality of longitudinally-movable lead-grippers, operating means to move said grippers longitudinally, means to thrust the grippers out of gripping engagement with a lead in the pencil when the grippers are in a downward position, and means to thrust the grippers into gripping engagement with a lead in the pencil when the grippers are in an upward position.

24. In a step-by-step pencil, the combination of a plurality of longitudinally-movable lead grippers adapted to be rockingly mounted and formed at one end with lead-gripping jaws and at the other with outwardly movable arms, a member adapted to extend between said arms and to bear against the inner surfaces of the same, and operating means including said member for causing said jaws to engage and feed forward a lead in the pencil, to release their grip thereon, to move upwardly while out of engagement with the lead, and to re-grip the lead at a higher point.

25. In a step-by-step pencil mechanism, the combination of a plurality of reciprocable lead propelling grippers provided with jaws arranged for the reception of lead therebetween, means to reciprocate said grippers, and means to impart to said grippers a jaw-separating movement of definite extent at predetermined periods in the operation of the mechanism.

26. In a step-by-step magazine lead pencil,

the combination with a casing having a tip at its lower end, means to provide a magazine for containing a plurality of leads in the upper end of said casing, and means to permit leads to be moved successively from said magazine to said tip, of longitudinally-movable lead-gripping and feeding means, operating means movable in one direction to move the lead-feeding means downwardly and in the opposite direction to move the same upwardly, means to move the lead-feeding means into gripping engagement with a lead in the pencil toward the end of the upward movement of the lead feeding means, and means to move the lead-feeding means out of such gripping engagement before the beginning of the upward movement thereof.

27. In a step-by-step magazine lead pencil, the combination with a casing having a tip at its lower end, means to provide a magazine for containing a plurality of leads in the upper end of said casing, and means to permit leads to be moved successively from said magazine to said tip, of a plurality of longitudinally-movable lead-gripping jaws, an exteriorly accessible actuating member, and operating means acting normally to hold said grippers in a retracted position and in gripping engagement with a lead in the pencil and acting in response to the operation of said actuating member first to advance the jaws and the lead as a unit, then to release the jaws, then to move the jaws upwardly, and thereafter to thrust the jaws into gripping engagement with the lead at a higher point.

28. In a step-by-step pencil, the combination of a plurality of longitudinally movable lead grippers adapted alternately to grip and release a lead in the pencil and to propel the same step-by-step, means to reciprocate said grippers, and stationary means in the path of said grippers to cause the grippers to grip a lead when moved against the stationary means.

29. In a step-by-step pencil, the combination of a casing member, a member movable longitudinally with respect to said casing a plurality of grippers adapted to be reciprocated in response to movement of the longitudinally movable member, and stationary means connected with said casing to move said grippers into and out of engagement with a lead toward the end of their upward and downward movements respectively.

30. In a step-by-step pencil, the combination of a casing member, a member movable longitudinally with respect to said casing member, a plurality of longitudinally movable lead grippers adapted to be moved downwardly within said casing in response to the downward movement of said longitudinally movable member, a plate beneath said grippers, resilient means tending to press said plate upwardly, and stationary means adapted to move said grippers into and out of engagement with a lead.

gagement with a lead toward the end of their upward and downward movements respectively.

31. In a step-by-step pencil, the combination of a plurality of longitudinally movable lead grippers, means to reciprocate said grippers, means to impart to said grippers lead-gripping and lead-releasing actions at different periods in the cycle of movement thereof, and a plate spring-pressed against said grippers and resisting lead-gripping and lead-releasing action thereof.

32. In a step-by-step pencil, the combination of a plurality of longitudinally movable lead grippers, means to reciprocate said grippers, means to cause said grippers to grip a lead in the pencil when the grippers are in an upward position, means to cause said grippers to release their hold on the lead when the grippers are in a downward position, a member tending to retain said grippers in a lead-gripping position until the operation of said last-mentioned means and to retain said grippers in a lead-releasing position until the operation of said grip-causing means.

33. In a step-by-step pencil, the combination of a casing, a lead-gripping and -feeding unit reciprocable within said casing and comprising a plurality of lead-gripping jaws, and a spring-pressed member formed with an inclined surface in the path of movement of said gripping unit for causing a lead-gripping action by said jaws, and means including said spring-pressed member to cause said jaws to propel a lead step-by-step through the pencil.

34. In a step-by-step pencil, the combination of a longitudinally movable member, a longitudinally movable lead-gripping and -feeding unit comprising a plurality of lead-gripping jaws, means to mount said lead-gripping and -feeding unit independently of said longitudinally movable member, and means responsive to the movement of said longitudinally movable member first to move said jaws and a lead gripped thereby downwardly as a unit, then to cause said jaws to release their grip on the lead, to move upwardly and to regrip the lead at a higher point.

35. In a step-by-step pencil, the combination of an exteriorly accessible longitudinally movable member, longitudinally movable lead-gripping means comprising a plurality of jaws, means to mount said gripping means independently of said exteriorly accessible member, means to maintain said gripping means normally in firm gripping engagement with a lead in the pencil, and means responsive to the movement of said exteriorly accessible member to cause said gripping means first to move downwardly while in engagement with a lead, then to release the grip on the lead, and then to move upwardly and to regrip the lead at a higher point.

36. In a step-by-step pencil, the combina-

tion of a casing member, a pencil cap arranged for movement in a direction toward said casing member, a plurality of longitudinally movable lead-gripping jaws, means to mount said jaws independently of said pencil cap, means normally to retain said jaws in firm gripping engagement with a lead, and means responsive to the movement of said cap in said direction to cause said jaws to move downwardly, to release their grip on the lead, and thereafter to move upwardly and regrip the lead at a higher point.

37. In a step-by-step lead pencil, the combination of a longitudinally-movable member, a plurality of longitudinally-movable pivotally-mounted lead-gripping jaws, means tending to hold said jaws firmly in gripping engagement with a lead in the pencil, means responsive to the downward movement of said longitudinally-movable member to cause said jaws to carry the lead downwardly therebetween, to release their grip on the lead, to move upwardly, and to regrip the lead at a higher point.

38. In a step-by-step lead pencil, the combination of a longitudinally-movable member, a plurality of longitudinally-movable lead-gripping jaws arranged to be reciprocated in response to the longitudinal movement of said longitudinally-movable member, and means with which said jaws are adapted to contact at a predetermined point in the movement of said jaws in each longitudinal direction for swinging said jaws into and out of engagement with a lead, whereby said jaws will propel a lead step-by-step through the pencil.

39. In a step-by-step lead pencil, the combination of a longitudinally-movable member, a plurality of longitudinally-movable lead-gripping jaws arranged to be reciprocated in response to the longitudinal movement of said longitudinally-movable member, and means with which said jaws are adapted to contact toward the end of the downward movement of said jaws for swinging said jaws out of engagement with a lead, and means for swinging said jaws into engagement with a lead at a higher point thereon, whereby said jaws will propel a lead step-by-step through the pencil.

40. In a step-by-step lead pencil, the combination of a longitudinally-movable member, a plurality of longitudinally-movable lead-gripping jaws arranged to be reciprocated in response to the longitudinal movement of said longitudinally-movable member, and means with which said jaws are adapted to contact toward the end of their upward and downward movements, respectively, for swinging said jaws into and out of engagement with a lead, whereby said jaws will propel a lead step-by-step through the pencil.

41. In a step-by-step pencil, the combina-

- tion of a casing member, a pencil cap arranged for movement in a direction toward said casing member, a plurality of pivotally-mounted lead-gripping jaws contained within 5 in said casing member, and means responsive to movement of said pencil cap in said direction to reciprocate said jaws and to impart lead-gripping and lead-releasing action thereto at relatively upper and lower jaw 10 positions, whereby the lead will be propelled step-by-step through the pencil.
42. In a step-by-step magazine lead pencil, the combination of a casing member, a longitudinally movable tubular member, means including 15 said tubular member to provide a lead magazine in the upper part of the pencil, a plurality of longitudinally movable jaws adapted when in an upward position to grip a lead therebetween, a gripper-operating member movable with said tubular member to impart downward movement to the jaws, and means including said gripper-operating member and responsive to a downward
- movement of said tubular member to cause 25 said jaws to carry a lead downwardly therebetween, to release their hold on the lead, to move upwardly, and to regrip the lead at a higher point.
43. In a step-by-step lead pencil, the combination of a longitudinally-movable member, a plurality of longitudinally-movable lead-gripping jaws arranged to be reciprocated in response to the longitudinal movement of said longitudinally-movable member, means to maintain said jaws in engagement 30 with a lead during the major part of their downward movement, and means with which said jaws are adapted to contact at a predetermined point in the movement of said jaws in each longitudinal direction for swinging 35 said jaws into and out of engagement with a lead, whereby said jaws will propel a lead step-by-step through the pencil.

In testimony whereof I affix my signature.

ALFRED WOELM.

DISCLAIMER

1,700,246.—*Alfred Woelm, Berlin, Germany. STEP-BY-STEP LEAD PENCIL. Patent dated January 29, 1929. Disclaimer filed January 20, 1933, by the assignee, Pencil Mechanism Corporation.*

Hereby enters this disclaimer, and disclaims from the scope of claim 25 of said Letters Patent any combination not including means disposed in the path of movement of the grippers to impart to said grippers a jaw-separating movement of definite extent at pre-determined periods in the operation of the mechanism.

[*Official Gazette February 7, 1933.*]

DISCLAIMER

1,700,246.—*Alfred Woelm, Berlin, Germany. STEP-BY-STEP LEAD PENCIL. Patent dated January 29, 1929. Disclaimer filed October 12, 1939, by the assignee, Penmac Corporation.*

Hereby enters this disclaimer to claim 33 in said specification.
[*Official Gazette November 14, 1939.*]

- tion of a casing member, a pencil cap arranged for movement in a direction toward said casing member, a plurality of pivotally-mounted lead-gripping jaws contained within 5 in said casing member, and means responsive to movement of said pencil cap in said direction to reciprocate said jaws and to impart lead-gripping and lead-releasing action thereto at relatively upper and lower jaw 10 positions, whereby the lead will be propelled step-by-step through the pencil.
42. In a step-by-step magazine lead pencil, the combination of a casing member, a longitudinally movable tubular member, means including 15 said tubular member to provide a lead magazine in the upper part of the pencil, a plurality of longitudinally movable jaws adapted when in an upward position to grip a lead therebetween, a gripper-operating member movable with said tubular member to impart downward movement to the jaws, and means including said gripper-operating member and responsive to a downward
- movement of said tubular member to cause 25 said jaws to carry a lead downwardly therebetween, to release their hold on the lead, to move upwardly, and to regrip the lead at a higher point.
43. In a step-by-step lead pencil, the combination of a longitudinally-movable member, a plurality of longitudinally-movable lead-gripping jaws arranged to be reciprocated in response to the longitudinal movement of said longitudinally-movable member, means to maintain said jaws in engagement 30 with a lead during the major part of their downward movement, and means with which said jaws are adapted to contact at a predetermined point in the movement of said jaws in each longitudinal direction for swinging 35 said jaws into and out of engagement with a lead, whereby said jaws will propel a lead step-by-step through the pencil.

In testimony whereof I affix my signature.

ALFRED WOELM.

DISCLAIMER

1,700,246.—*Alfred Woelm, Berlin, Germany. STEP-BY-STEP LEAD PENCIL. Patent dated January 29, 1929. Disclaimer filed January 20, 1933, by the assignee, Pencil Mechanism Corporation.*

Hereby enters this disclaimer, and disclaims from the scope of claim 25 of said Letters Patent any combination not including means disposed in the path of movement of the grippers to impart to said grippers a jaw-separating movement of definite extent at pre-determined periods in the operation of the mechanism.
